US00D761483S

(12) **United States Design Patent**
Pratt et al.

(10) **Patent No.:** US D761,483 S
(45) **Date of Patent:** ** Jul. 12, 2016

(54) **LUMINAIRE**

(71) Applicant: **CREE, INC.**, Durham, NC (US)

(72) Inventors: **S. Scott Pratt**, Cary, NC (US); **William L. Dungan**, Cary, NC (US); **Kurt S. Wilcox**, Libertyville, IL (US); **Nicholas W. Medendorp, Jr.**, Raleigh, NC (US); **Brian Kinnune**, Racine, WI (US); **Gary David Trott**, Eatonton, GA (US)

(73) Assignee: **Cree, Inc.**, Durham, NC (US)

(**) Term: **14 Years**

(21) Appl. No.: **29/499,708**

(22) Filed: **Aug. 18, 2014**

(51) **LOC (10) Cl.** 26-99

CLAIM

The ornamental design for the luminaire, as shown and described.

DESCRIPTION

FIG. 1 is a top isometric view of the ornamental design for the luminaire;

FIG. 2 is a bottom isometric view of the luminaire of FIG. 1; FIG. 3 is a front elevation view of the luminaire of FIG. 1, the rear elevation view being a mirror image thereof;

FIG. 4 is a top plan view of the luminaire of FIG. 1; and,

FIG. 5 is a bottom plan view of the luminaire of FIG. 1.

The evenly spaced broken lines in all FIGS. illustrate environmental portions of the luminaire that form no part of the claimed design. The dot-dash lines depicted in FIGS. 1, 2, 3 & 5 are used to indicate the bounds of the claimed design and the dot-dash lines form no part of the claimed design.

1 Claim, 4 Drawing Sheets
